UNITED STATES PATENT OFFICE.

GEORGE S. DAVY AND RAPHAEL S. VINCENT, OF MADISON, WISCONSIN.

RAILROAD TIE.

Application filed November 8, 1928. Serial No. 318,020.

The present invention relates to railroad ties and the objects and advantages thereof will become apparent from the following detail description taken in conjunction with 5 the accompanying drawings, wherein:

Figure 1 is a side elevation of the tie embodying the features of our invention,

Figure 2 is a top plan view thereof,

Figure 3 is a transverse section there- 10 through taken substantially on the line 3—3 of Figure 1,

Figure 4 is a fragmentary longitudinal horizontal section taken through one end of the tie substantially on the line 4—4 of Figure 1,

Figure 5 is an enlarged detail top plan view of a portion of the tie where the rail rests thereon,

Figure 6 is a detail longitudinal section 20 taken substantially on the line 6—6 of Figure 5,

Figure 7 is a fragmentary detail plan view 25 of the tie where the rail rests thereon showing the same with the clamp removed, and

Figure 8 is a detail transverse section taken substantially on the line 8—8 of Figure 7.

Referring to the drawings in detail it will be seen that the numeral 5 denotes an oblong body of concrete in which is imbedded an 30 I beam denoted generally by the letter A. This I beam A includes a vertically disposed web 6 extending longitudinally of the body 5 and connecting together upper plate 7 and lower plate 8, the latter being narrower than 35 the former.

The bottom plate 8 is located just below the center of the vertical dimension and below this plate 8 there is disposed reinforcement including rectangular frame 9 and 40 rod 10 with upstanding ends, the rod 10 extending longitudinally of the frame 9 along the center longitudinal dimension thereof and the frame 9 extends longitudinally of the body 5 and reinforces what we term the 45 bed of the body.

Portions a of the plate 7 are exposed 50 through the top of the body 5 so that rails may rest thereon and also so that clamps may be engaged therewith. The ends of the portions a are corrugated as indicated at 55 12, longitudinally slotted as at 13, the slots at their outer ends terminating in enlarged openings 14.

Corresponding recesses 15 are provided 55 below openings 14 in the body 5 and drain

openings 16 lead therefrom. These recesses 15 continue under the slots 13 for accommodating the heads of bolts 17. Thus the heads of the bolts may be placed through the openings 14 and then the shanks of the bolts 60 slid into the slots 13.

The body 5 is humped upwardly as is indicated at 19 between the portions a and as at 20 beyond the portions a so as to cover the I beam except portions a and also for the 65 purpose of draining off rain water and the like in an expeditious manner. Clamp plates 22 have corrugated under faces 23 and the inner ends of these plates are offset upwardly to provide portions 24 overhanging 70 the bases of the rails resting on the portions a and are provided with openings to receive bolts 17 so that nuts 17' may be threaded thereon to clamp the plates 22 on the corrugated portion 12 with the overhanging portions 24 over the bases of the rail thus effectively eliminating any danger of the clamp plate slipping on the plate 7 and yet allowing for any necessary adjustment.

In this way it is permissible to firmly engage 80 the rails on the tie in an easy manner yet in a thoroughly effective, efficient and reliable manner.

From the above detailed description it will be seen that we have devised a railroad 85 tie which is simple in its construction, strong and durable, inexpensive to manufacture, and thoroughly efficient and reliable in use.

The shape of the tie as shown and described 90 protects all reinforcements from corrosion except where fastened to the rail which parts are protected with any of the well known anti-rust compounds. The fastenings and the I beam reinforcements prevent the rails from spreading, tipping over 95 or getting out of proper gauge and are preventive of the so-called "sun kink".

It is thought that the construction, utility 100 and advantages of the tie will now be clearly understood by those skilled in this art without a more detail description thereof. The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination 110

and arrangement of parts may be made without departing from the spirit and scope of the claim.

Having thus described our invention, what we claim as new is:

A railroad tie comprising an elongated concrete body, and an I beam embedded in said body and extending longitudinally thereof and terminating short of the opposite ends thereof, the upper face of the body being curved arcuately longitudinally thereof intermediate its ends and arcuately at its

ends at points spaced from the terminals of the central curved portion, said beam having portions of its upper plate exposed through the top of the body between the central and end curved portions to provide rail seats, and rail clamping means engaging said seats.

In testimony whereof we affix our signatures.

GEORGE S. DAVY.
RAPHAEL S. VINCENT.
